UNITED STATES PATENT OFFICE.

RALPH D. MERSHON, OF NEW YORK, N. Y.

ALTERNATING-CURRENT MACHINE.

No. 857,958.

Specification of Letters Patent.

Patented June 25, 1907.

Application filed July 5, 1904. Serial No. 215,238.

To all whom it may concern:

Be it known that I, RALPH D. MERSHON, a citizen of the United States, residing at New York, in the county and State of New York, have invented certain new and useful Improvements in Alternating-Current Machines, of which the following is a specification, reference being had to the drawings accompanying and forming part of the same.

10 My invention relates to alternating current machines, both generators and motors, which are adapted to have the number of their poles varied, and has for its object to provide means for introducing into the secondary element devices which by their effect modify the operation of the machine. Among such devices may be mentioned resistances, reactances, and capacities, as well as such other devices as may lend themselves to such uses. My invention therefore does not reside in the broad combination of these devices therewith, but rather in the provision of such connections for these devices that they are effectively utilized at the times when their 25 effects are desired.

As is well known, in the case of an induction motor, for example, better results are obtained in starting the motor if there is introduced into the secondary a resistance, 30 which is cut out as the motor comes up to speed. But in order to obtain this rheostatic control, which involves switching or the equivalent, it has been necessary to employ slip rings on one element of the motor, or to 35 have a commutating switch in the rotating secondary, operated by a rod or lever, or by devices actuated by centrifugal force. It has therefore been proposed to use a permanent resistance, in the secondary, which is a 40 compromise between the best starting resistance, and the lowest resistance which is best for running conditions. This plan also possesses obvious disadvantages.

In my invention, however, employed with 45 machines in which the number of poles is varied, a high resistance or any other suitable device may be used in starting, or in running at low speeds, but will have no detrimental effect on the operation of the motor when the 50 speed thereof is increased and the number of poles reduced. This result is attained by the manner of connecting the resistance or other device with the secondary winding, the connections being so arranged that a given device will be effective for one number of poles, and non-effective or less effective for other

numbers of poles. Several sets of devices may be used, over as wide a range of pole numbers as desired, each set being adjusted or proportioned for a particular number of 60 poles, and so connected with the secondary winding or windings that for each number of poles there will be effective in the secondary, a device, or set of devices, which is suited or adjusted for such number of poles. Also, 65 the connections for the respective devices, or sets thereof, are such that those effective for a higher number of poles become ineffective or less effective for succeeding lesser numbers. In other words the devices are cut in 70 or out, as it were, in succession as the different numbers of poles are produced in the primary, and this cutting in or out is not caused by the actuation of any mechanical parts in the secondary circuits, but results entirely 75 from the nature of the connections between the devices and the secondary windings. The invention therefore possesses none of the disadvantages inherent in collector rings, or in commutating switches, etc., which have 80 heretofore been employed for analogous purposes, in cases where the device is small enough to be included in the secondary element. When the device or devices are of such nature that they cannot be so included, 85 slip rings or similar instrumentalities will have to be used but in such case, as also in the case of a stationary secondary, the use of any form of switch for cutting the modifying devices in or out is rendered unnecessary. 90

My invention will be more readily understood when explained in connection with the accompanying drawings. In explaining the principle of the invention, single phase machines with salient poles and ring wound 95 secondaries are shown, for the sake of clearness, and in these figures no means for varying the number of poles is illustrated, that effect, for purposes of explanation, being secured by the use of different primaries. 100 In other figures, however, the machine is shown as a single phase one adapted for variation in the number of its poles, the method chosen being that of leading currents in at the proper points in the primary winding. 105

It will be understood that the invention is applicable to motors or generators of any other type, both single and polyphase, and with uniformly or non-uniformly distributed windings whether of the ring or drum type. 110 It is also immaterial whether the different numbers of poles are all produced by the

same winding, or by different windings or combinations of windings, in both primary and secondary elements. As a matter of fact, in practice the best results will be obtained with distributed windings, where the different numbers of poles are produced by different windings, or by leading in the currents at the proper points in the same winding.

10 c. In the drawings, Figure 1 shows diagrammatically a two pole motor, having a ring secondary short circuited across one diameter. Fig. 2 shows a four pole motor with the same secondary. Fig. 3 shows a four pole motor, having its secondary short circuited across four electrical diameters. Fig. 4 shows an eight pole motor, with the secondary illustrated in the preceding figure. Fig. 5 is a diagram illustrating my invention applied to a motor adapted to be run with two or four poles. Fig. 6 shows a modification of the same. Fig. 7 is an arrangement for two, four, and eight poles. Fig. 8 illustrates diagrammatically a drum or squirrel-cage secondary embodying my invention, with a high resistance for four poles and a low resistance for two poles. Fig. 9 illustrates diagrammatically a single phase motor with my invention embodied therein, and capable 30 of running at two or four poles. Figs. 10 and 11 illustrate diagrammatically secondary elements in which both resistances and condensers are used for one number of poles, the condenser and resistance being in multiple in Fig. 10 and in series in Fig. 11.

35 Throughout the various figures of the drawings A designates the motor primary, and B the motor secondary, wherever these elements appear.

40 Referring now to Fig. 1, the magnetic flux from pole to pole through the secondary winding is indicated by the dotted lines. Across the diameter of the secondary is a short circuit, 1, which in the position shown 45 is effective to its fullest extent. In any other position it is less effective, but there may be any number of diametrical short circuits so that in any position the secondary will be effectively short circuited. But if 50 the secondary of Fig. 1 be put in the field of Fig. 2, which has four poles, it is not short circuited for the flux of the latter field, as will be seen from an inspection of the figure, in which the flux relation to the conductor 55 may be noted. In order to have a short circuit effect with four poles in the primary or, in fact, with any number of poles, the short circuits must be across electrical diameters, as at 1^a in Fig. 3, or across chords less than 60 the electrical diameter. From the explanation before given in connection with Figs. 1 and 2, it will be seen that an effective short circuit of Fig. 3 in every position may be obtained by short circuiting a number of electrical diameters of the secondary. Putting

this secondary in the field of Fig. 4, which has eight poles, there is again no short circuit effect; and to produce this effect it is necessary to place the short circuits across electrical diameters of one-eighth the circumference. It is seen, therefore, that short circuits across electrical diameters in Fig. 1 are

70 not effective in Fig. 2; and that those which are effective in Fig. 3 are not effective in Fig. 4. The converse, however, is not true, for 75 short circuit across electrical diameters in Fig. 4 are effective in Fig. 3 and are effective also in Figs. 2 and 1. That is the short circuit across the electrical diameter for the lower number of poles is not effective for the 80 higher number, but the short circuit across the electrical diameter of a higher number of poles is effective for a lower number.

85 Keeping the above in mind, suppose that when the motor is running at a greater number of poles it is desirable to have in the secondary circuits resistances, for example. These resistances may be inserted in the short circuit paths across the electrical diameters for the greater number of poles and they 90 will then be ineffective for the lesser number of poles because when the motor is operating at the lesser number of poles the resistances are, in effect, shunted by a path of no resistance—a short circuit path. In this case, 95 therefore, not only are the short circuits for the lesser number of poles ineffective for the greater number of poles but also the resistances for the greater number of poles are ineffective or practically so for the lesser number 100 of poles.

105 In general, suppose the machine is to be capable of operation at two or more numbers of poles and that for each number of poles there is to be in the secondary an effect equivalent to that of certain resistances the value of the certain resistances to be less as the pole numbers are diminished. The resistances across electrical diameters for the greatest number of poles are those effective 110 for that number of poles. The equivalent effective resistance for the next lower number of poles will be one whose value lies between that for the greatest number of poles and that due to the resistances across the 115 electrical diameters of the lower number of poles and will be controlled by the value of the latter resistance. The equivalent resistance for the next lower number of poles will be one lying between the effective resistance 120 for the preceding number and that across the electrical diameter for the next lower number and controlled by it and so on down to, if desirable, a number of poles whose electrical diameters are short circuited. In this case 125 therefore each number of poles may have certain definite effective resistances effective for that number of poles and for none of the other pole numbers employed. The same explanation applies to other devices than 130

sistances whether the devices be all of the same nature or not. This will be clearly seen from Fig. 5. This figure shows a single phase motor provided with leads m, m', m'', m''' by which it may be run at two poles or at four.

C indicates a diagrammatic controller connecting the motor with the single phase source D. By tracing the connections it will be seen that in the first position of the controller leads m, m'' will be connected with the source, producing two poles. In the second position all the leads are connected with the source, producing four poles. The secondary, B, in a two pole primary, is shown with resistances in the four pole short circuits, and none in the two pole short circuits.

As previously explained, in a case like Fig. 5 there would be a greater number of two pole and four pole paths than are shown, the others being omitted from the diagram to avoid complicating the figures. As shown in Fig. 5 there are two short circuits for the two pole condition, 90 degrees apart, while the four pole conductors or paths are 180 electrical degrees apart, considered from the standpoint of four poles. In practice there would probably be, for the greatest number of poles, at least two sets of paths, in quadrature; and there might be others at other angles. There are also other connections which give an equivalent effect, and which are somewhat simpler than those just described. For example, as will be at once seen, the arrangement shown in Fig. 6, in which the resistance R is connected between the short-circuits 1^b is the equivalent of the connections shown in Fig. 5.

As previously stated, any number of sets of devices may be used in the secondary. In Fig. 7 is shown diagrammatically a secondary for a machine in which the number of poles in the primary may be eight, four and two. The resistances shown as included in the secondary circuits are inserted on the "equivalent" plan illustrated in Fig. 6. That is, the method of connection is a series one rather than the multiple arc shown in Fig. 5. In Fig. 7, when the motor is running with eight poles all the resistances are active, when the pole number is changed to four the resistances r, r' become inactive or nearly so, when the pole number is two the resistances r', r'' become inactive or nearly so, especially if, as will usually be the case the resistances r'', r''' have as low a value as possible, that is, constitute a short circuit. It will be noted that the paths are 90 electrical degrees apart for the eight pole connection, 45 electrical degrees apart for the four pole, 22.5 electrical degrees apart for the two pole. In the latter case of course electrical degrees and degrees of arc are the same. In practice there might be many more paths than are shown.

As previously explained, the device to be used in the secondary may be a resistance, a reactance, or a capacity, etc. For example, if a properly constructed capacity be introduced into the secondary of an induction motor the torque of the motor may be enormously increased at low speeds, but this torque will in general diminish rapidly as the speed of the motor rises toward synchronism for that number of poles to which the introduction of the condenser corresponds, because in approaching this speed the voltage and frequency impressed upon the condenser diminish.

In Fig. 9 is shown a motor arranged to operate with two and with four poles with resistances R' in the secondary for the two pole connection and condensers E for the four pole connection. In this figure the motor is connected with the single phase source D through a diagrammatic controller C' and by tracing the connections it will be seen that in the first position of the controller the leads m^4 and m^5 will be connected with the source, producing two poles, and in the next position all the leads, m^4, m^5, m^6, m^7 will be connected with the source, producing four poles. If the capacity of the condenser be properly proportioned, on starting the motor with the four pole connection a strong torque will be produced, which will fall off as the motor approaches synchronism for four poles. But when the torque has diminished to a point below that required the motor may be switched off of the four pole connection on to the two pole connection, which connection will then produce a higher torque than it would at starting, because the motor has increased in speed toward that at which the two pole connection would give its highest torque. Or, instead of a condenser alone, a condenser and resistance in parallel, or in series, might be used, as in Figs. 10 and 11 respectively. In the case of using the condenser alone, and under some circumstances where the combination of condenser and resistance is used, the primary connections for four poles may be retained even after the two pole connection has been made. When connected in this way the two devices in the secondary will take currents which in general will be independent of each other, as will also their corresponding currents in the primary winding or windings. In consequence the resulting current delivered to the primary element by the supply circuit will be a resultant of the two primary currents due to the secondary currents just mentioned. The same course may be resorted to with more than two numbers of poles; and also with any other devices or sets of devices whether the nature of the devices for each number of poles be the same or not.

Where a combination of condenser and resistance is desirable an electrolytic con-

denser may be used, which, because of its high internal loss, will perform the functions of both condenser and resistance.

Because of the well known reversibility of the induction motor in that when driven above synchronous speed it will act as a generator, the scheme described herein with particular reference to an induction motor applies equally well to induction generators.

10. What I claim is:

1. In an alternating current machine, adapted for variation in the number of its poles, the combination with the primary element, of a secondary element, devices or sets of devices in the secondary element for modifying or improving the operation of the machine with two or more numbers of poles, and permanent connections for said devices or sets of devices with the secondary winding or windings at such points that said devices or sets of devices become successively more effective in their action as the number of poles is increased, as set forth.

2. In an alternating current machine, adapted for variation in the number of its poles, the combination with the primary element, of a secondary element, devices or sets of devices in the secondary element for modifying or improving the operation of the machine with two or more numbers of poles, and permanent connections from said devices or sets of devices to the secondary winding or windings at such points, relative to the number of poles, that said devices or sets of devices become successively more effective in their action as the number of poles is increased, as set forth.

3. In an alternating current machine, adapted for variation in the number of its poles, the combination with the primary element, of a secondary element, devices or sets of devices in the secondary element for modifying or improving the operation of the machine, permanent connections from said devices or sets of devices to the secondary winding or windings, at such points that the said devices or sets of devices are less effective or non-effective in their action for one number of poles and more effective for a greater number of poles, additional devices or sets of devices in the secondary element for modifying or improving the operation of the machine, and permanent connections therefrom to the secondary winding or windings at such points that said additional devices or sets of devices are less effective or non-effective for said greater number of poles and more effective for a still greater number of poles, as set forth.

4. In an alternating current machine, adapted for variation in the number of its poles, the combination with the primary element, of a secondary element, devices or sets of devices in the secondary element for modifying or improving the operation of the ma-

chine, permanent connections from said devices or sets of devices to the secondary winding or windings, along electrical diameters for one number of poles, additional devices or sets of devices in the secondary element for modifying or improving the operation of the machine, and permanent connections therefrom to the secondary winding or windings along electrical diameters for another number of poles, as set forth.

5. In an alternating current machine, adapted for variation in the number of its poles, the combination with the primary element, of a secondary element, resistances in the secondary element, and permanent connections for said resistances with the secondary winding or windings at such points that said resistances become successively more effective in their action as the number of poles is increased, as set forth.

6. In an alternating current machine, adapted for variation in the number of its poles, the combination with the primary element, of a secondary element, resistances in the secondary element, permanent connections from said resistances to the secondary winding or windings at such points that the said resistances are less effective or non-effective in their action for one number of poles and more effective for a greater number of poles, additional resistances in the secondary element, and permanent connections therefrom to the secondary winding or windings at such points that said additional resistances are less effective or non-effective for said greater number of poles and more effective for a still greater number of poles, as set forth.

7. In an alternating current machine, adapted for variation in the number of its poles, the combination with the primary element, of a secondary element, resistances in the secondary element, and permanent connections from said resistances to the secondary winding or windings along electrical diameters for two or more numbers of poles, whereby said resistances become successively effective or more effective in their action as the number of poles is increased, as set forth.

8. In an alternating current machine, adapted for variation in the number of its poles, the combination with the primary element, of a secondary element, short circuits in the secondary element along electrical diameters for the minimum number of poles with which the machine is to be operated, devices in the secondary element for modifying or improving the operation of the machine with two or more numbers of poles, and permanent connections for said devices with the secondary winding or windings at such points that said devices become effective or more effective in succession as the number of poles is increased, as set forth.

10. In an alternating current machine, adapted for variation in the number of its poles, the combination with the primary element, of a secondary element, devices or sets of devices in the secondary element for modifying or improving the operation of the machine with two or more numbers of poles, and permanent connections for said devices with the secondary winding or windings at such points that said devices become effective or more effective in succession as the number of poles is increased, as set forth.
